UNITED STATES PATENT OFFICE.

THOMAS HOCKING LUCAS, OF MINNEAPOLIS, MINNESOTA.

GRATE.

SPECIFICATION forming part of Letters Patent No. 700,061, dated May 13, 1902.

Application filed June 3, 1901. Serial No. 62,969. (No model.)

To all whom it may concern:

Be it known that I, THOMAS HOCKING LUCAS, of Minneapolis, in the county of Hennepin and State of Minnesota, have invented a new and useful Improvement in Grates, of which the following is a specification.

My invention is an improvement in grates, and has for an object to provide a simple easily-operated grate especially adapted for burning fine and crumbling fuel, such as peat, sawdust, lignite, bituminous slack, and anthracite pea-coal. A difficulty has been experienced in the burning of this class of fuel from the fine particles falling unconsumed through the grate whenever an attempt is made to remove the ashes, thus wasting a large quantity of fuel. This is particularly the case with lignite, which crumbles as soon as it comes in contact with heat, and any agitation of the fire will cause the fine particles to fall through the grate with the ashes, leaving on the grate the coarser pieces which have not ignited to smolder and emit a very offensive gas that would otherwise be consumed by the combustion of the finer particles could they be retained.

The purpose of my invention, therefore, is to provide a grate capable of retaining all fuel until consumed to ashes and then to release the ashes without interfering with the unconsumed fuel.

The invention consists in certain novel constructions and combinations of parts, as will be hereinafter described and claimed.

In the drawings, Figure 1 is a vertical cross-section of my grate on about line 1-1 of Fig. 3. Fig. 2 is a detail plan view of the shaker-section. Fig. 3 is a top plan view of the grate, and Fig. 4 is a bottom plan view of the grate; and Fig. 5 is a bottom plan view of the fixed or main section, the shaker-section being removed.

With the above-described purpose in view I construct my grate with a main or fixed section A and a shaker-section B, which latter is so connected with the fixed or main section that it can be moved to the right or to the left, giving a rotary movement, or can be moved forward and backward when it is desired to expose larger spaces in order to dis-

charge the ashes more rapidly or when any foreign substance may have been introduced into the fire-pot.

The main or fixed section A is in the form of a basket depressed toward its bottom and having its sides composed of bars A', inclining inwardly toward its bottom, as shown. The bottom comprises a frame A², which is crossed from side to side by bars a², which are spaced apart at a³ sufficiently (see Fig. 5) to permit a quick discharge of the contents of the grate when the movable section B is adjusted to expose the said spaces a³ between the bars a².

The shaker-section B has a handle B', a frame B², that normally underlies the frame A² of the bottom, and end bars b and cross-bars b', one for each of the spaces a³, so the sections B can be adjusted, as shown in Fig. 4, to extend across and nearly close the openings a³, as will be seen in the said figure.

Connecting devices are provided between the shaker-section B and fixed section A, so the former can be moved revolvably or back and forth, as may be desired.

In connecting the sections A and B, I prefer to provide a pivot-stud C, depending from the under side of the section A and forming a journal for the section B, so the latter can rock, its bearing-opening for the stud or shaft C being a slot D, elongated from front to rear to permit the back-and-forth reciprocating movement of the section B before described.

Now in operation, when the parts are adjusted as shown in Fig. 4 the openings in the bottom of the grate are so slight as to prevent the escape of the finely-divided fuel and at the same time permit the desired passage of air to support combustion. At the same time the grate-section B can be rocked slightly from side to side to gently discharge the ashes without disturbing the unconsumed fuel, and if it is desired to shake more vigorously or dump the fire the section B may be moved back and forth to any desired degree. It will also be understood that my improved grate can be used for finely-divided or the ordinary grate fuel, the manipulation of the section B being suited to the character of fuel employed.

Having thus described my invention, what I claim as new, and desire to secure by Letters Patent, is—

- 5 1. The grate herein described comprising the main or basket section having a bottom frame provided with cross-bars spaced apart and with side bars inclining inwardly toward the bottom frame, a depending pivot-stud on the bottom frame, and the shaker having a handle and a frame and cross-bars adapted to partly close the spaces between the bars of the bottom of the main section and a bearing opening or slot for the pivot-stud elongated from front to rear whereby the shaker-section 10 can be oscillated with respect to a vertical axis and reciprocated, substantially as set forth.
- 15 2. The combination of the main or basket section provided with side bars and with the flat bottom having cross-bars, and the shaker-section supported below said bottom and capable of oscillating with respect to a vertical axis and reciprocating substantially as set forth.
- 20 25 3. The grate herein described having the main section provided with a bottom having openings, and the shaker-section supported to oscillate with respect to a vertical axis and to reciprocate beneath said bottom substantially as set forth.
- 30 35 4. The combination of the grate-section having a depressed or basket form, and the shaker arranged close beneath the grate-section and capable of oscillating with respect to a vertical axis and of reciprocating substantially as set forth.
5. The combination of a fixed or main grate-section having a depressed or basket form and a movable shaker close beneath said section

and capable of oscillating with respect to a vertical axis and of reciprocating substantially as set forth.

6. A grate comprising the main section having its bottom formed of cross-bars spaced apart, and the shaker-section supported close below the said bottom and having its cross-bars formed to partly close the spaces between those of the grate-bottom, such shaker being capable of oscillating with respect to a vertical axis and of reciprocating substantially as set forth.

7. A grate composed of a main fixed section and a shaker-section below the fixed section, the entire shaker-section being arranged and supported to oscillate with respect to a vertical axis and to reciprocate beneath the fixed section substantially as set forth.

8. The combination of the fixed-section having a stud and a shaker-section having an elongated opening or slot receiving the stud, whereby the shaker-section can be oscillated with respect to a vertical axis and reciprocated, substantially as set forth.

9. The grate herein described, comprising the basket-section having its bottom formed with cross-bars, and provided on said bottom with a depending pivot-stud, and a shaker comprising a frame and cross-bars, and provided with a vertical opening for the passage of the stud of the basket-frame, said opening being elongated whereby the shaker-section can be oscillated around the pivot-stud as a vertical axis, and can be reciprocated below the basket-section substantially as set forth.
